UNITED STATES PATENT OFFICE.

SOL. F. STEVER, OF FAIRFIELD, IOWA.

RAILWAY-RAIL JOINT.

SPECIFICATION forming part of Letters Patent No. 289,465, dated December 4, 1883.

Application filed December 29, 1882. (No model.)

To all whom it may concern:

Be it known that I, SOL F. STEVER, a citizen of the United States, residing at Fairfield, in the county of Jefferson and State of Iowa, have invented a new and useful Improvement in Railway-Rail Joints, (which invention has not been patented to me, or to others with my consent or knowledge, in any foreign country,) of which the following is a specification.

My invention relates to improvements in railway-rail joints; and the objects of my invention are to confine the binding hook or clasp to its place by means of a stop on each side of the joint, which will prevent the hook or clasp from sliding in either direction, and will thus keep the joint always closely bound together.

I am aware that fish-plates and angle-bars have heretofore been used, and that a binding-clasp such as is herein described has heretofore been used to hold a railway-rail joint together.

Figure 1 of the accompanying drawings represents a general view of my improved joint. Fig. 2 represents an end view or cross-section of the joint. Fig. 3 represents the clasp or double hook, which passes under the angle-bars in my joint and binds them against the rails. Fig. 4 represents my improved angle-bar, showing its general form and the stop on its edge to hold the clasp in position. Fig. 5 represents another form of my improved angle-bar, used only on the outside of the rails to make a continuous rail at the joint. Fig. 6 represents an end view of the joint with an outside angle-bar of the form shown in Fig. 5.

The following is a detailed description of the drawings explaining my invention and the manner of constructing and using it.

Similar letters refer to similar parts in all the figures of the drawings.

R R' represent the ends of two ordinary railroad-rails meeting in the joint at j, Fig. 1.

P P' represent my improved fish-plates or angle-bars, called in this specification "angle-bars." They are made of wrought or rolled iron, steel, or other equivalent material in the form shown in the drawings, and so as to fit the sides of the rails, extending beyond the edges of the web or bottom of the rail on each side a distance equal to half the width of the

bottom of the rail, giving the joint a bottom or surface to rest upon the cross-ties or sleepers twice as wide as the rail. The sides of the angle-bars through which the cross-bolts b b pass are full or flush with the sides of the crown of the rails. The angle-bars are interchangeable, so that each bar may be used either on the inside or on the outside of the rails, and they are so used indifferently. The angle-bars P P' are held against the sides of the rails R R', and the joint is bound together by two means: first, by bolts passing through the angle-bars, and the intervening rails secured by nuts, or nuts and washers, as in the joints with fish-plates and angle-bars now in common use; second, by the clasp or double hook H H described below. The notches n n are for the passage of ordinary railroad-spikes to fasten the joint to the cross-ties or sleepers.

The clasp or double hook H is made of wrought-iron, steel, or other equivalent material, in the form shown by the figures. It passes under the angle-bars P P' and the intervening rails, R R', and clasps the angle-bars on each side against the rails firmly and securely by the hooks h h at each end. It is held in its place and prevented from slipping lengthwise along the edges of the angle-bars by the stops s s, one of which is on the edge of each angle-bar, and so placed that the stop on the edge of the outside angle-bar prevents the clasp from slipping in one direction, and the stop on the edge of the inside angle-bar prevents it from slipping in the opposite direction. The joint is constructed by placing one of my improved angle-bars P on one side of the railroad-rails, which are brought together at the middle of the angle-bar, with the angle-bar placed closely against the rails, as in Fig. 1. The clasp H is placed under the angle-bar, with one of the hooks h h clasping the outer edge of the angle-bar and resting against the stop s. Another of the angle-bars is slipped along the opposite side of the rails, passing under the other hook h of the clasp H, until its stop s comes against the clasp H in the position shown in Fig. 1. The apertures in the angle-bars and in the intervening rails for the cross-bolts b b will then be in line. The cross-bolts are passed through these aper-

tures. The nuts on the points of the bolts are screwed up until they press against the angle-bars or against the washers on the bolts, and the joint is bound together by them. The joint is then ready to be fastened to the cross-ties or sleepers by driving ordinary railroad-spikes through the notches $n n$.

Another form of my improved angle-bar (shown by C in Figs. 5 and 6) is used only on the outside of the rails, in the place of one of the angle-bars P, the inside of the joint being formed by the other angle-bar, P, as described above. It makes a continuous rail at the joint, as is shown by Fig. 6. It is made of the same materials and in the same manner as the angle-bar P, above described; but the form is modified, as is shown by the drawings and as described below. It is of the same general dimensions as the angle-bar P. It has the stop s , the notches $n n$, and the apertures for the bolts, and is made to fit closely against the sides of the rails, as in P; but it has a crown or head extending its entire length, whose width on top is three-fourths the width of the rail. The top of this crown or head is on the same level as the top of the rail, so that it will receive the tread of the car-wheels and carry them past the junction, thus making a continuous rail at the joint. This crown or head is supported by the increased thickness of the

part of the angle-bar C which fits against the stem r of the rails, and through which the cross-bolts pass, which gives it the same strength as the rails themselves. The crown or head is a little lower at the ends than in the middle, and slopes gradually from each end to the middle, so as to prevent any jarring or clicking when the wheels come upon it. The joint shown in Fig. 6 is put together in the same manner as the joint shown in Fig. 1, which is described above. I am aware that railway-rail joints have been made prior to my invention by the use of fish-plates and angle-bars of various forms, which were placed along the sides of the rails, and bolts were passed through the plates or bars and the intervening rails. I do not therefore, in broad terms, claim a joint so made; but

What I do claim as my invention, and desire to secure by Letters Patent, is the following:

In a railway-rail joint, the stop s , in combination with the fish-plates or angle-bars P P' and the clasp H, substantially as described in the foregoing specification.

SOL. F. STEVER.
